(57) **CLAIM**

The ornamental design for a van with two doors, as shown and described.

DESCRIPTION

FIG. 1 is a perspective view from the front and right side of a van with two doors showing my new design;

FIG. 2 is a perspective view from the front and left side thereof;

FIG. 3 is a perspective view from the rear and left side thereof;

FIG. 4 is a perspective view from the rear and right side thereof;

FIG. 5 is a rear view thereof;

FIG. 6 is a front view thereof; and

FIG. 7 is a right side view thereof;

FIG. 8 is a left side view thereof; and,

FIG. 9 is a top view thereof.

The broken lines in the drawings illustrate portions of the elements which form no part of the claimed design.

1 Claim, 8 Drawing Sheets(56)
